ROOM AIR CONDITIONING UNIT

Robert R. Fink, Duluth, Minn., assignor to International Telephone and Telegraph Corporation, a corporation of Maryland

Application February 4, 1953, Serial No. 23,445

Term of patent 7 years

(Cl. D62—4)

To all whom it may concern:

Be it known that I, Robert R. Fink, a citizen of the United States, residing at Duluth, in the county of St. Louis and State of Minnesota, have invented a new, original, and ornamental Design for a Room Air Conditioning Unit, of which the following is a specification, reference being had to the accompanying drawing, forming a part hereof.

Figure 1 is a perspective view of a room air conditioning unit embodying my new design.

Figure 2 is a front elevation view of the room air conditioning unit with the upper movable grill in a different position.

The other side of the air conditioning unit, not visible in Figure 1, is substantially the same as the side shown.

I claim:

The ornamental design for a room air conditioning unit, as shown and described.

ROBERT R. FINK.
